HYDRAULIC CONTROL FOR FUEL
SELECTOR VALVES

Henry E. Hull, Cleveland, Ohio, assignor to The
Parker Appliance Company, Cleveland, Ohio, a
corporation of Ohio

Application November 22, 1943, Serial No. 511,330

4 Claims. (Cl. 121—41)

1

This invention is a device for selectively indexing and correspondingly adjusting a selector valve to any of its various flow-control positions.

Very often in airplane practice, the fuel selector valve is mounted in an inaccessible place, and several universal joints and the like must be employed in the single control shaft between the valve and the operating handle in the cockpit of the plane. This results in considerable free play of the handle which is objectionable. One of the objects of the present invention is to overcome this difficulty by simplifying the mechanical connections in the control shaft between a selector valve and an operating handle, whereby free play of the handle, and other lost motion is practically avoided. A further object is to provide a selector-valve-control means of simple construction, and which may be readily attached to selector valves now in general use.

The invention will be hereinafter fully set forth and particularly pointed out in the claims.

In the accompanying drawings:

Figure 1 is a view showing the control device in vertical section, the selector valve controlled thereby being illustrated diagrammatically in association therewith.

Figure 2 is a horizontal section of the control member on the line 2—2, Figure 1, with an illustrative form of a manually operating valve and its connections with the control device being also shown.

Figure 3 is a vertical section on the line 3—3, Figure 2, and at right angles to the section of Figure 1.

Figure 4 is a longitudinal sectional view illustrating the manually operated valve for indexing the control device.

Figures 5 and 6 are detail sectional views illustrating a modified form of the control device.

Figure 7 is a sectional view illustrating another modified form of the invention.

Referring more particularly to Figures 1, 2, 3 and 4, SV designates a selector control valve which is diagrammatically illustrated, and may be of any form now in common use characterized by a movable valve member which is actuated by means of a rotative valve stem S. In this connection, it is to be understood that although the invention will be hereinafter described as applied to the fuel control system of an airplane, it is not intended to limit the invention in this particular, because obviously the specific use of the selector valve is immaterial.

In the form of the invention disclosed by the figures above mentioned, a casing C for a fluid

pressure motor is provided, the same comprising a ring-shaped casing 10, having a plurality of vent ports arranged circumferentially thereof. Said ports correspond in number and in spacing to the positions to which the fuel selector valve must be adjusted. Four vent ports 11^a, 11^b, 11^c and 11^d are shown for purposes of illustration. There is also a fluid pressure port F. Said casing has a cylindrical bore therethrough which is closed at its ends by cap members 12 and 13 to provide a closed pressure chamber 14, thereby providing a cylindrical pressure chamber. The casing C is preferably rigidly attached to the casing of the selector valve SV by means of a plurality of studs 15 and spacer tubes 16, as shown.

Rotatively mounted within the chamber 14 is an axially disposed, tubular valve-actuator shaft 20, the same being mounted in the cap members and journaled at one end in a needle bearing 21 in the cap 12, the other end of the shaft being passed through a stuffing box 22 of any suitable character. Said shaft 20 is provided with a longitudinally disposed rectangular slot 23 intermediate of its ends. A flat valve-actuating vane 24 is provided with a tapered inner end 25, which is extended into said slot in such manner, that the vane will be caused to travel in an arcuate path when the shaft 20 is rotated. The outer end of said vane engages the inner surface of casing 10, and this engagement is yieldingly maintained by means of spring pressed plungers 26 having tapered ends 26^a which coat with tapered surfaces 25 of the vane to urge the latter radially outward. It will be noted that the plungers 26 are reciprocatively mounted within the shaft 20, one spring 26^b being abutted against the cap 12, the other spring 26^b being abutted against a closed end of the shaft 20. The shaft 20 is operatively connected to the fuel selector valve stem S by means of a yoke driver 27, fixed to the shaft, and a yoke 28, fixed to the selector valve stem. As shown, the stuffing box 22 comprises a gland and a pair of O ring type seals.

Mounted within the casing C is a sector-like abutment H, which is fixed in position by means of pins 30 which pass through the bulkhead and are anchored in the cap members 12 and 13—see Figure 3. The bulkhead has an inlet passage 31 communicating with the fluid pressure port F, and is provided with a coupling member adapted to be connected with any suitable source of fluid pressure. Said inlet passage 31 is provided with two discharge branches 32, 33 respectively, which are positioned to discharge two independent

fluid pressure streams into the pressure chamber, and on opposite sides of the vane 24, so as to normally maintain a uniform fluid pressure within the chamber 14 while venting thereof is prevented through the vent ports, and thereby hold the vane 24 in stationary position.

Leading from the respective vent ports 11^a, 11^b, 11^c and 11^d are outlet pipes 36^a, 36^b, 36^c and 36^d, which lead to correspondingly positioned inlet ports 37^a, 37^b, 37^c and 37^d in a valve casing V. Rotatively mounted in said casing is a plug 39, having an angularly disposed venting channel 40, one branch of which is positioned to be selectively registered with the respective ports 37^a, 37^b, 37^c and 37^d, its other branch being connected with a vent port 41.

In operation, assuming that the vane 24 is in the position illustrated in Figure 2, with its outer end covering port 11^c, and that the valve V is positioned as shown in the same figure, it will be observed that the fluid pressure medium which is at all times entering the chamber 14 under an approximately constant pressure, cannot pass out of any of the vents 11^a, 11^b, 11^c or 11^d. Therefore, a balanced pressure is maintained against the opposite sides of the vane 24, so that it will not move. Now assuming that it is desired to move the vane 24 a distance of 180°, so as to impart a similar movement to the valve stem S, the plug 39 of valve V will be moved to place its exhaust branch 40 with the port 37^a in communication with the conduit 36^a leading from outlet port 11^a. The effect of this is to vent the chamber 14 through said port 11^a and its conduit 36^a and through plug 39 to the reservoir. Thereupon, the pressure of the incoming fluid against the right hand side of the vane 24 as viewed in Figure 2, will be greater than it is on the other side, because the fluid will vent faster through the outlet port 11^a than it can be supplied through the topmost discharge branch 32 of the inlet passage 31. Thereupon, the vane 24 will move in a clockwise direction until its outer end closes the vented port 11^a. Movement of the vane imparts a corresponding movement to the shaft S in the same direction and to the same extent. Just as soon as the vane 24 closes the vented outlet port 11^a, the equalized pressure upon opposite sides of the vane is immediately established, and the vane will therefore remain in this position until the valve V is again actuated. Obviously, the arrangement is such that the vane may be caused to move to any selected vent port by manually moving the valve plug 39 to a position which will vent the selected port to the atmosphere. The operation will be exactly the same as above described and repetition therefore is considered unnecessary.

The form of the invention illustrated in Figures 5 and 6 is a modified arrangement for quickly reestablishing the pressure balance against the vane after it has travelled the desired predetermined direction. In this form, the pressure chamber is constructed as illustrated in Figures 1, 2 and 3, and the manual control valve is substantially as shown in Figures 2 and 4. The abutment H, however, is provided with a cylindrical bore 50, which extends across the pressure inlet port F, at right angles thereto, and communicates therewith. The ends of said bore also open into the pressure chamber. Reciprocatively mounted within said bore is a balance shuttle valve BV, which comprises a cylindrical body 51 of approximately the same diameter as that of said bore, and having longitudinally spaced re-

duced portions 52, leaving a central portion 51 of a length somewhat less than the diameter of the port F. The ends of the valve BV are of tubular form, as indicated at 54, and ports 55 extend through the tubular ends from the reduced portions 52. The shuttle valve BV is maintained in a normally central balanced position with respect to the port F, by means of springs 56 which engage the respective ends of the valve and bear against the pins 34 as abutments. As previously stated, the length of the central portion 51 of the shuttle valve is less than the diameter of the port F, so that while said shuttle valve is in central position the pressure fluid may pass in opposite directions through the ports 55 and into the chamber 14 through the ends of the bore 50. By this arrangement a balanced pressure against the opposite sides of the vane 24 is maintained. Just as soon as the valve V is adjusted to selectively vent the chamber 14 through any one of the ports 11^a, 11^b, 11^c or 11^d, the pressure on one side of the vane will be greater than the other for reasons fully described in connection with the operation of the previously described form of the invention. At the same time the pressure upon the same side of the shuttle valve 51 will also be greater so that the latter will be shifted to close the communication between the pressure inlet and the opposite branch of the bore 50. This reduces the extent of pressure applied to that side of the vane 24, and this condition is maintained until the vane moves to cover the selected vented opening. As soon as it tends to pass said last mentioned opening to the slightest degree, further escape of the fluid pressure through that opening is arrested, and the unbalancing pressure against the shuttle valve will be rectified, so that the two springs 56 will bring the valve BV to its normal neutral position, and immediately effect balancing of the pressure on opposite sides of the vane 24.

Figure 7 represents a modified form of the control mechanism, particularly with respect to the control of the flow of pressure fluid from a suitable source to the pressure chamber. Referring to said figure, the casing C¹ is substantially the same construction as that illustrated in the other figures, already described, but is provided with a plurality of circumferentially spaced ports, four being shown for purposes of illustration, and respectively marked A, B, C and D. The shaft 20^a and the vane 24^a are substantially the same as the corresponding elements previously described. The abutment H¹ located within the chamber C¹, is not provided with the pressure fluid supply features of the previously described figures. In lieu thereof, a balanced valve casing BV¹ is shown, the same being provided with a valve chamber 60 which is connected to a suitable source of pressure fluid supply by a conduit 61. Said chamber communicates with a cross bore 62, in which is reciprocatively mounted a shuttle valve SV¹ similar to that illustrated in Figures 5 and 6, and described in detail in connection therewith. In other words, said valve is provided with a body portion 63, which is held in a central position with respect to the chamber 62 by means of opposed springs 64. The valve body is of a length somewhat less than the width of chamber 62, so that while the valve is in its neutral or balanced position under the tension of said springs, pressure fluid may pass from the valve chamber to either of conduits 65 and 66, respectively. The conduit 65 is connected with vent port A through a conduit a. The conduit 66 is connected with the port

B of the pressure chamber by means of a pipe b. The valve casing BV¹ is supported by a base member 11, which is provided with an exhaust channel 11. Said channel communicates with the conduit a by means of a pipe a¹, so that pressure fluid may be vented through the port A. The outlet to the conduit a¹ is normally closed by a spring pressed poppet valve P¹. In a similar manner the exhaust conduit 11 is connected by means of conduit b² with pipe b, and through the latter to the vent B. It will be noted that the abutment H¹ is located between ports A and B. The outlet of conduit b² is normally closed by a similar poppet valve P². The exhaust conduit 11 is connected with port C by means of a conduit c, normally closed by a poppet valve P³. In a similar manner the port D is connected with the exhaust channel by means of a conduit d, which is also normally closed by a poppet valve P⁴. Conduits 65 and 66 are also connected with conduits a and b, respectively.

It is to be understood that a constant supply of fluid under pressure is normally maintained in the valve chamber 60, and through conduits 65 and a, and 66 and b to the casing C¹, and that all of the poppet valves are normally closed by their springs. It will be clear that by this means a balanced fluid pressure is maintained on opposite sides of the vane 24^a. Assuming that the vane 24^a is in the position illustrated in Figure 7, a manual depression of the poppet valve P¹ will vent the chamber C¹ at the vent A through conduits a and a¹ and exhaust conduit 11, thereby lowering the pressure between the vane and the adjacent side of the abutment H¹. At the same time, the constantly flowing pressure fluid will travel by way of conduits 66 and b to the chamber C¹ through vent B, on the other side of the abutment, so as to apply pressure on the adjacent side of the vane, whereupon the latter will travel in a clockwise direction until its outer end covers the port A. Simultaneously with the foregoing operation, the pressure of the incoming pressure fluid against the valve BV¹ will force it to move in a direction to close the conduit 65, so that the incoming pressure fluid cannot interfere with the exhaust through the conduit a¹. This condition maintains until the vane travels the predetermined distance to close the port A, whereupon the balancing of the pressures of the springs 64 will immediately restore valve BV¹ to its central or neutral position. The effect of this is to promptly balance the pressures applied to both sides of the vane. If it should be desired to move the vane in the other direction, the extent of movement in that direction will be determined by which of the poppet valves P², P³ or P⁴ is operated. Assuming that the poppet valve P⁴ is depressed, the pressure fluid would be introduced into the chamber C¹ through the port A and exhausted through the port B, whereupon the vane will travel the necessary distance to close the last mentioned port, and the balancing valve will automatically resume its neutral position, thereby reestablishing the pressure balance on the vane. It is believed that the effect of the depression of any one of the other poppet valves is readily understandable from what has been previously described, and therefore, further detail description thereof appears to be unnecessary.

The advantages of the invention will be readily understood by those skilled in the art to which it belongs. For instance, it will be observed that a very simple mechanical connection is provided in

the control shaft between a selector valve and an operating handle; so constructed and arranged that all unnecessary play is avoided. It will also be noted that the device is sensitive and accurate. In other words, the control unit handle is turned exactly 100°, for example, in order to turn the fuel selector valve a precisely corresponding extent. Another important advantage is that the device is capable of being readily attached to selector valves of types now in general use.

Having thus explained the nature of the invention and described an operative manner of constructing and using the same, although without attempting to set forth all of the forms in which it may be made, or all of the forms of its use, what is claimed is:

1. A selector valve actuating device comprising a normally closed annular pressure chamber, a rotatively mounted valve-operating shaft axially disposed within said chamber and having a longitudinal slot therein, a vane having a tapered end extended into said slot, the other end of said vane engaging the peripheral wall of said chamber, spring pressed plungers engaging the tapered end of the vane so as to yieldingly maintain the latter in engagement with the wall of the chamber, means for introducing fluid under pressure into said chamber on both sides of said vane, so as to maintain a balanced pressure upon opposite sides thereof while said chamber is closed, and means for selectively venting said chamber at any one of a plurality of preselected circumferential positions, whereby the fluid pressures upon the sides of said vane will be unbalanced and the vane will be caused to travel to the vented location.

2. A selector valve actuating device comprising a normally closed annular pressure chamber, a hollow valve-operating shaft rotatively mounted within said chamber in an axial position with respect thereto, said shaft having a longitudinal slot, a vane having a tapered end extended into said slot, the other end of the vane having slideable engagement with the peripheral wall of said chamber, spring pressed plungers located within said shaft and engaging the adjacent end of the vane, so as to yieldingly maintain the engagement of the latter with said wall, means for introducing fluid under pressure into said chamber on both sides of said vane, so as to maintain balanced pressures upon opposite sides thereof while said chamber is closed, and means for selectively venting said chamber at any one of a plurality of preselected circumferential positions, whereby the fluid pressures upon the sides of said vane will be unbalanced and the vane will be caused to travel to the vented location.

3. An activating device for adjusting selector valves to pre-selected flow positions comprising a normally closed annular chamber provided with a plurality of circumferentially spaced peripheral vent ports located to index the desired valve adjustment positions, a hollow shaft rotatively mounted within said chamber, a vane radially disposed with respect to said shaft and free to move radially therethrough, means within said shaft for applying yielding lateral pressure upon said vane so as to maintain the outer end of the vane in engagement with the peripheral wall of the chamber in a position to close any of said ports, said vane when at rest normally occupying a position closing a pre-selected vent port, a fluid pressure conduit connected with said chamber and having means for delivering equal-

ized fluid pressure into the chamber on opposite sides of the vane so as to hold the latter in a normally stationary position, means for selectively venting said chamber at any one of said vent openings so as to unbalance the fluid pressures upon the sides of the vane, whereby when any selected vent is opened, other than the one closed by said vane, the pressures will become unbalanced and the vane will be caused to travel to the vented opening, so as to shut off flow of fluid pressure through the chamber, the vane being at all times free to move to any selected open vent irrespective of its previous position of rest.

4. A selector valve actuating device comprising relatively spaced end caps and an intermediate annular member rigidly connected to provide a normally closed annular pressure chamber, a hollow valve-operating shaft rotatively mounted in said end caps and positioned axially with respect to said chamber, said shaft having a longitudinal slot therein a vane having its inner end slidably movable within said slot and movable with the shaft, and its other end engaging the peripheral wall of the chamber, means within said shaft for yieldingly applying a lateral pressure against said vane so as to maintain the engagement of the vane with said peripheral wall, means for introducing fluid under pressure into said chamber on both sides of said vane, so as

to maintain balanced pressures upon opposite sides thereof while said chamber is closed, and means for selectively venting said chamber at any one of a plurality of preselected circumferential positions, whereby the fluid pressures upon the sides of said vane will be unbalanced and the vane will be caused to travel to the vented location.
